Primary Examiner—Raphael Barkai*Attorney, Agent, or Firm*—Armstrong, Westerman, Hattori, McLeland & Naughton[57] **CLAIM**

The ornamental design for a socket for manual tool, as shown and described.

DESCRIPTION

FIG. 1 is a front elevational view of the socket for manual tool showing our new design, the rear elevational view being a mirror image thereof;

FIG. 2 is a top plan view of the socket for manual tool;

FIG. 3 is a bottom view of the socket for manual tool;

FIG. 4 is a right side elevational view of the socket for manual tool, the left side elevational view being a mirror image thereof;

FIG. 5 is an enlarged cross sectional view along the line 5—5 of FIG. 1 of the socket for manual tool;

FIG. 6 is a view of the socket for manual tool in use; and, FIG. 7 is a view of the socket for manual tool in use.

The broken lines shown in FIGS. 6 and 7 are for illustrative purposes only and form no part of the claimed design.
